(57) **CLAIM**

I claim the ornamental design for a scissors handle, as shown and described.

DESCRIPTION

FIG. 1 is a front perspective view of one embodiment of a scissors handle showing my new design, in accordance with the present invention;

FIG. 2 is a front plan view of the scissors handle of FIG. 1 shown as part of a pair of scissors;

FIG. 3 is a back plan view of the scissors handle of FIG. 1;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the FIGURES illustrate the environment or unclaimed portions of the scissors handle and form no part of the claimed design. Specifically, dashed lines represent unclaimed elements of the design, dot-dash lines represent an environment around the design, and dot-dot-dash lines indicate the boundary between the claimed and unclaimed features of the design.
